UNITED STATES PATENT OFFICE.

FRANCISCO P. IANNARONE, OF WASHINGTON, DISTRICT OF COLUMBIA.

SEAL-LOCK.

SPECIFICATION forming part of Letters Patent No. 253,388, dated February 7, 1882.

Application filed August 31, 1881. (No model.)

To all whom it may concern:

Be it known that I, FRANCISCO P. IANNARONE, a citizen of the United States, residing at Washington city, District of Columbia, have 5 invented new and useful Improvements in Packing-Boxes, of which the following is a specification.

My invention relates to certain new and useful improvements in packing-boxes, and more 10 particularly to that class known and used as coin or shipping boxes.

The object of my invention is to obtain positive security against accidental or fraudulent removal of the lid; and with these ends in 15 view my invention consists in providing the cover or lid of the box with a lock on the under side having two or more bolts adapted to secure the lid against removal, and the hub or central portion of said lock, through which 20 the key passes, countersunk and provided with a covering-plate adapted to conceal and cover the key-hole, said covering-plate being adapted for use with a paper or other seal, as will be hereinafter set forth.

25 My invention further consists in the details of construction hereinafter fully set forth and specifically claimed.

In order that others skilled in the art may know how to make and use my invention, I 30 will proceed to describe the construction and operation of the same, referring by letters to the accompanying drawings, in which—

Figure 1 is a bottom plan view of the lid or cover of my improved box, showing a three-bolt lock and independent catch-bar. Fig. 2 is a central longitudinal and vertical section 35 through a box embodying my invention. Fig. 3 represents a bottom view of the covering-plate which conceals the key-entrance to the lock 40 proper. Fig. 4 is a plan or top view of the central cap-plate of the lock with the covering-plate removed. Fig. 5 is a plan view of the lock, exposing the bolts and bolt-operating mechanism. Fig. 6 is a central section taken 45 horizontally through Fig. 5. Fig. 7 is a side or edge view of the cap-plate shown at Fig. 4; and Fig. 8 is a section taken at line *x x*, Fig. 4.

Similar letters indicate like parts in the several figures.

A represents a rectangular wooden box, which preferably has arranged centrally and at right angles to each other two countersunk strengthening iron bands, B B, near the upper ends of which are provided bolt-holes or openings, through which the lock-bolts pass. These bands are secured by screws C, and hold the sides, bottom, and ends of the box securely in place. D is the top, which is rabbeted around the edges to permit the lock-bolts to move in 55 a plane below the top edges of the box and guard them against attack from the outside.

At the center of the cover or top of the box, on the inside, is arranged the lock-case E, which is secured in place by screws F, or in any other 60 suitable manner.

The lock shown consists of three radiating bolts, the inner ends of which are provided with rack-teeth meshing with a centrally-arranged pinion adapted to be operated by an 65 ordinary key.

The top of the box is mortised or cut away over said lock to receive the hub G of cap-plate H, through which pass two or more screws, I', the threads of which pass into the 70 top plate of the lock-case E, and thus hold the cap-plate in position. This cap-plate is provided with a key-hole, J, to permit the passage of the key to the lock below; and it is furnished also with another key-hole, K, ar- 75 ranged within which is a post, L, secured to a bracket, M, on the under side of the plate.

N and O are two rectangular openings in 80 said plate to receive hooks secured to the under side of a guard-plate presently described.

Arranged underneath the opening N is a spring-latch, P, and in line with and slightly behind the opening O is arranged a flat spring, Q, one end riveted to the under side of plate, F, and the other provided with a stud, R, which 85 passes through an orifice in the plate H, and in its normal position projects slightly above the same.

On each side of the key-hole K are arranged two or more sharpened studs or points, S, 90 adapted to pierce and hold stationary a paper or other puncturable seal.

The cap-plate is formed with an annular rim, T, which is designed to come flush with the top of the box and high enough to receive within 95

it a guard-plate, U, having a key-hole, V, corresponding with the key-hole K in the cap-plate, and two hooks, *a b*. Each side of the key-hole, V, are two depressions, *c c*, adapted 5 to receive the points S S. The plate U is placed in position by passing the hook *a* through the opening O and under the plate H, and then, by pressing on the opposite side of the guard-plate, forcing the beveled hook *b* under the spring-latch P. The key-holes K V are arranged to one side of the spring-latch P, and the latter is adapted to be operated by 10 a suitable key. Before placing the guard-plate in position a paper or other easily-punctured seal is placed over the hole K, and the points S S caused to penetrate and hold the same against lateral movement, so that when the plate U is latched in place it cannot be removed except by the withdrawal of the latch 15 20 by a key, the entrance of which must destroy the seal.

The seals used may be in triplicate—one furnished with the bill of lading, one placed under the guard-plate, and one kept with the 25 stub or inclosed in the box; but in this particular any predetermined system may be adopted.

To remove the guard-plate a key is forced through the seal under the key-hole V, and by turning the key the spring-latch P is withdrawn 30 from the hook *b*, and when the hook is released the spring-stud R forces the plate upward sufficiently far for it to be grasped to withdraw the hook *a* from its seat, when the plate may be entirely removed, thus exposing 35 the cap-plate over the lock, and through which cap-plate the lock may be operated.

The box may or may not be furnished with any suitable grasps or handles.

I do not wish to confine myself to any special feature of construction in the lock proper 40 or the number of bolts used, as any character of lock mechanism may be used, the gist of my invention in this particular resting in the idea of providing the lock with a cap-plate, access to which is obtained only by the removal of a 45 guard-plate.

What I claim as new, and desire to secure by Letters Patent, is—

1. In combination with the lock secured on the under side of the lid of the box, and a cap-plate having a key-hole through which the lock-operating key is passed, a concealing guard-plate, U, provided with a key-hole, V, out of register with the key-hole of the lock and adapted to receive a different key, so that the 50 guard-plate must be unlocked and removed before access can be had to the key-hole of the lock, substantially as hereinbefore set forth.

2. In combination with the plate H, provided with openings N O and latch P, and the guard-plate U, provided with hooks *a b*, the spring-stud R, substantially as and for the purpose 60 set forth.

In testimony whereof I have hereunto set my hand and seal in the presence of two subscribing 65 witnesses.

F. P. IANNARONE. [L. S.]
